UNITED STATES PATENT OFFICE.

SWAIN THACKARA, OF CAMDEN, NEW JERSEY.

ELECTRICAL TIME-PIECE.

SPECIFICATION forming part of Letters Patent No. 351,222, dated October 19, 1886.

Application filed May 14, 1886. Serial No. 202,171. (No model.)

To all whom it may concern:

Be it known that I, SWAIN THACKARA, a citizen of the United States, residing in Camden, Camden county, New Jersey, have invented certain Improvements in Electrical Time-Pieces, of which the following is a specification.

My invention relates to that class of electrical time-pieces which are operated by successive electrical impulses governed by the circuit-closing device of one standard time-piece, and the object of my invention is to construct a simple and accurate time piece of this character, which can be operated by comparatively small electro-magnetic power, and in which the hands can be set backward or forward with equal facility. This object I attain in the manner which I will now proceed to describe.

In the accompanying drawings, Figure 1 is a vertical section on the line 1 2, Fig. 2, of sufficient of an electrical clock to illustrate my invention. Fig. 2 is a section on the line 3 4, Fig. 1; and Figs. 3, 4, and 5 are views illustrating the devices in different positions.

A A are the front and back plates of the clock united by the rods or bars a , a' , and a'' .

D is the main arbor, adapted to bearings in the front and back plates and carrying a ratchet-wheel, d , to which an intermittent rotary motion to the extent of one tooth is imparted at each electrical impulse, as hereinafter described.

E is the electro-magnet, which in the present instance I have shown as consisting of two bobbins carried by the cross-bar a' , which forms the base of the horseshoe. The armature F of this electro-magnet is carried by a bent lever, f , pivoted at f' at the base of the electro-magnet—that is, at the opposite end from the armature F. A spring, g , tends to keep the armature in the elevated position illustrated in the drawings, and in contact with the back stop, p ; but when the circuit is closed through the coils of the electro-magnet the armature will be moved in the arc of a circle by the magnetic attraction both toward the poles and across their faces, tending toward the central position, (shown by dotted lines in Fig. 2,) when the armature-lever comes into contact with a front stop, p' , which in the present instance I have shown as carried

by or forming part of the cross-bar a'' . Owing to this pivoting of the armature-lever at the base of the electro-magnet in the manner illustrated, I obtain a long leverage and a strong magnetic action upon the armature, so that comparatively little battery power is consumed in operating the armature, and, moreover, a compact arrangement is provided. The armature-lever or its pivot also carries an arm, M, to the upper end of which is pivoted the pawl m , adjacent to the periphery of the ratchet-wheel d . The outer face of this pawl is beveled, and is adapted to come into contact with the beveled face of each of the teeth of the ratchet-wheel successively, so that instead of the ordinary pulling action of a pawl and ratchet, I move the ratchet-wheel by the beveled face of the pawl coming against the beveled face of the tooth and sliding thereon, as indicated in Figs. 3 and 4, so that when the armature-lever has come into contact with the front stop the pawl will be at the bottom of the space between adjacent teeth, as illustrated in Fig. 4, so that there will be no jumping action produced on the hands of the time-piece, and when, on the breaking of the circuit, the spring returns the armature-lever to its normal position, the pawl m will turn on its pivot and slide back over the tooth, as indicated in Fig. 5, to its normal position, Fig. 1, without disturbing the wheel.

Instead of a pawl to prevent back action of the ratchet-wheel as usually employed, I make use of a friction device, which in the present instance is shown as consisting of a spring, s , carried by the cross-bar a and bearing on the main arbor D. By this means, and as the operating-pawl m is normally out of contact with the ratchet-wheel d , the hands of the time-piece can be moved in either direction to set them.

The above-described actuating device can be used for the second-hand movement as well as for the hour and minute movements, if desired. In the drawings, I have shown gearing for minute and hour movements only, there being mounted on the main arbor, outside of the front plate, a pinion, 1, engaging with a gear-wheel, 2, carrying a pinion, 3, which in turn gears with a wheel, 4, free to turn on the main arbor, and carrying the hour-hand K,

while the main arbor itself projects through the axis of the wheel 4 and carries the minute-hand L.

The terminal wires of the electro-magnet 5 may be suitably connected to insulated binding-posts P P'.

I claim as my invention—

1. An electric-clock actuator, comprising the ratchet-wheel, with an electro-magnet and armature-lever carrying a pivoted pawl having a beveled working-face to engage with the beveled working-faces of the teeth of the ratchet-wheel, substantially as described.

2. An electric-clock actuator, comprising an arbor and ratchet-wheel, with an adjacent electro-magnet lever, f, pivoted at the base of the magnet and having an arm, N, at an angle thereto, carrying a pivoted pawl to engage with the ratchet-wheel, all substantially as described. 15

In testimony whereof I have signed my name 20 to this specification in the presence of two subscribing witnesses.

SWAIN THACKARA.
